UNITED STATES PATENT OFFICE.

MAX LANGER, OF BERLIN, GERMANY, ASSIGNOR TO SIEMENS & HALSKE AKTIEN-
GESELLSCHAFT, WERNERWERK, OF SIEMENSTADT NEAR BERLIN, GERMANY.

CIRCUIT ARRANGEMENT FOR AUTOMATIC TELEPHONE SYSTEMS.

Application filed July 5, 1927, Serial No. 203,322, and in Germany July 13, 1928.

The invention relates to automatic telephone systems, in which all circuit changes, which are necessary during the setting up and existence of a connection, are effected 5 over one signalling line common to several junction lines.

In the known arrangements of this kind the calling station receives the busy signal when all signalling lines are engaged, or with 10 semi-automatic working the operator is given no exchange signal, so that the impulse transmission has to be delayed until a signal line is free, thereby considerably delaying the setting up of the connection, especially 15 when the junction line traffic is dense.

Now the object of the present invention is to speed up the traffic, this being rendered possible by providing an impulse storer at the outgoing end of the signalling line. 20 When the signal line is engaged, the storer accepts the current impulses transmitted from the calling station and transmits them to the receiving devices at the incoming end of the signalling line when the latter 25 comes free.

The invention is illustrated by way of example in the drawing, which shows an arrangement for semi-automatic working over a trunk line.

For the purpose of describing the method of working this arrangement, it will first be assumed that the signalling line is free. When the number of the wanted subscriber has been communicated to the operator in known manner, she inserts the calling plug into the jack VK 1 of an idle junction line and inserts the plug 1 into the switch jack WK 1. The following sleeve circuit is then established: battery, resistance W_i , sleeve of 30 the jack WK 1, contact r , winding of the relay W , contact O at the third contact set of the switch W_1 , winding of relay An 1, contact t 1, earth. Relay W is operated, at its contacts w 1, w 2 it applies the exchange 35 signal to the speaking leads. Relay An 1 is likewise energized and switches over its contacts. At contact 1 *an* 1 it closes its own locking circuit and at contact 3 *an* 1 it opens the signalling lead. At contact 2 *an* 1 the 40 relay interrupter RU is connected up, which alternately opens and closes a circuit for the relay F . In response to these interruptions, the relay F 1 is energized and de-energized and at the same time its contact f 1 closes 45 and opens the circuit for the rotary magnet 50 D I of the switch W I. The rotary magnet moves on the wipers of the switch W I until they reach the line leads a' and b' taken into use by the operator.

At the incoming end of the signalling line 55 the wipers of the switch W II are moved on synchronously with those of the switch W I. At the same time intervals as for the rotary magnet D I, the relay F closes and opens the circuit for the rotary magnet D II over: 60 earth, contact f 2, winding of the rotary magnet D II, battery, earth.

The circuit of both the rotary magnets is finally opened as soon as the wipers of the switch W I reach the leads a' and b' . The 70 relays R and T are then operated over battery, resistance W_i , bush of the jack WK 1, winding of relay R , lead b' , corresponding contact at the second contact set of the switch W I, windings I and II of the relay 75 T , earth. Relay T at its contact t 1 interrupts the circuit of the relay An 1, which falls back and at contact 3 *an* 1 again switches through the signalling lead a 1. At the contact 2 *an* 1 the relay interrupter 80 is disconnected from the relay F , so that it can operate no more, and at contact f 1 it permanently opens the circuit of the rotary magnet D I and at contact f 2 that of the rotary magnet D II. The relay T at its 85 contact t 2 short circuits its high resistance winding and prevents the signalling line being taken into use over a line connected in multiple at the same contact of the switch. On being operated over the above described 90 circuit, the relay R at its contact r opens the circuit for the relay W , which falls back and at its contacts w 1 and w 2 disconnects the exchange signal from the speaking leads. This notifies the operator that she can dial. 95

During the return motion of the number dial, a circuit is closed and opened for the impulse repeating relay J at the incoming end of the signalling line a number of times corresponding to the selected number: earth, 100 impulse contact i , jack $W_k 1$, lead a' , contact and wiper of the switch W I 1, back contact 3 *an* 1, wiper and contact of the switch W II, winding of relay J , battery, earth. The relay J is alternately energized and de-energized. At the first impulse of current 105 its contact 1 2 closes a circuit for energizing its contacts v 1 and v 2 the relay V , which at its contacts v 1 and v 2

prepares the impulse loop to the impulse receiving relay at the succeeding connecting devices, and as the relay is slow to release, it holds up during the train of impulses. 5 At each impulse the contact i 1 closes and opens the loop. The circuit for this loop extends over: earth, impulse contact i 1, front contact v 1, a -lead, b -lead, front contact v 2, resistance W_i , battery, earth. An 10 other impulse contact i 3 closes the following circuit for energizing the relay C: earth, impulse contact i 3, back contact e 2, winding of relay C, back contacts e 1 and i 3, resistance W_i , battery, earth. The relay C 15 at contact c 2 closes its locking circuit and at contact c 3 it energizes the relay E by removing its short circuit: earth, front contact c 2, winding of relay C, winding of relay E, resistance W_i , battery, earth. At contact 20 c 1 is earthed the test lead to the succeeding connecting devices.

The selection having been ended, the relay V falls back and at its contacts v 1 and v 2 it switches through the speaking leads. 25 When the operator at the called trunk exchange or the called subscriber answers, the operator at the local exchange withdraws the plug 1 from the switch jack. Instead of removing the plug, the sleeve circuit could 30 be interrupted by means of a key. Thus the relays R and T are released. The relay An 1 is operated over earth, back contact t 1, winding of relay An 1, wiper and contact of the switch W I 3, resistance W_i , battery, 35 earth. At its contact 2 an 1 the relay connects up the relay interrupter. The relay F is alternately energized and de-energized and it operates the rotary magnet D I over its contact f 2. The wipers of the switches 40 W I and W II are moved on until the O position is reached. The circuit for the relay An 1 is then interrupted and the switches remain in their normal position. The devices of the signalling line have now 45 returned to their normal position, hence they can be used for establishing another connection.

At the end of the conversation the operator again closes the sleeve circuit. In 50 the manner above described, the switches again go into the position designated by the contacts, to which the leads a' and b' are connected. The exchange signal having ceased, the operator actuates the release key, 55 thereby giving a longer releasing current impulse to the connecting devices at the incoming end of the signalling line. Over the contact i 3 the relay C is short circuited and released so that earth is disconnected from 60 the test lead. At contact c 2 is interrupted the locking circuit for the relays C and E. At the end of the release current impulse, the relay E also falls back, thus these devices have been returned to their normal 65 position. The operator now withdraws the

plug 1 from the switch jack and this causes the relay T to fall back. The switches then go into their normal position, hence all the devices are in their normal position after the operator has withdrawn the calling plug 70 from the connecting jack VK 1.

It will now be assumed that all the signalling lines associated with the particular junction line are engaged. In that case the operator performs the same operations as 75 those already described. She receives the exchange signal when she inserts the plug 1 into the switch jack. The relay W is now operated over the following circuit: battery, resistance W_i , sleeve of the jack WK 1, back 80 contact r , winding of relay W, back contact g , contact O at the third contact set of the switch W III, winding of relay An 2, back contact u 5, earth. The relay W at its contacts w 1 and w 2 connects the exchange signal to the speaking leads. The relay An 2 is likewise energized; it closes the locking circuit for itself at contact 4 an 2 and at contact 3 an 2 it connects the relay interrupter RU 1 to the rotary magnet D III 90 of the switch W III. The rotary magnet moves on the wipers of the switch until they reach the contacts, to which the leads a' and b' are connected. The following circuit is then established: battery, resistance W_i , 95 sleeve of the jack WK 1, winding of relay R, lead b' , contact and wiper of switch W III, back contacts p and o 1, windings I and II of the relay U, earth. In this circuit the relays R and U are operated. The relay R interrupts the circuit of relay W, which at its contacts w 1 and w 2 disconnects the exchange signal from the speaking leads. By opening its contact, the relay R also prevents the leads a' and b' being connected to a signalling line that becomes free during the selecting operation, as this would cause the incomplete transmission of current impulses. The relay U at its contact u 5 interrupts the circuit of the relay An 2, which disconnects the interrupter RU 1 from the rotary magnet D III. The switch W III therefore remains standing on the contacts designated by the leads a' and b' . At contact u 1 the 100 high resistance winding of the relay U is short circuited and the storer is prevented from being taken into use by another party. At the contact 2 an 2 the circuit for the rotary magnet D V is prepared to receive 110 number impulses and at contact u 3 a circuit is prepared for the relay B.

If the operator now dials, this circuit is alternately closed and opened for the rotary magnet during the return of number dial. 115 The circuit extends from earth over the impulse contact i , jack WK 1, lead a' , corresponding contact and wiper at the second contact set of the switch W III, back contacts 2 an 2, p 2 and 5'', winding of the 120 130

rotary magnet D V to battery, earth. The rotary magnet D V moves on the wipers of the switch W V. The circuit of relay B is closed at the first impulse. The relay falls back slowly and holds up during the train of impulses. At the end of the first train of impulses, the relay B falls back and at its contact *b* it closes the following circuit for energizing the relay V: earth, back contact 5 *b*, wiper and contact at the second set of contacts of the switch W V, winding of relay V, battery, earth. The relay V actuates its contacts and at change over contact 10 *b* it switches the circuit for the number impulses to be received over to the rotary magnet D VI. At contact 5' is closed a circuit for keeping energized the second winding of relay V, this circuit having been prepared by the relay C I. When the relay 15 U was operated, the relay C I was energized over: earth, front contact *u* 4, back contact *s*, winding of relay C I, battery, earth. During the return motion of the number dial, the current impulses are transmitted to the 20 rotary magnet D VI, which moves on the wipers of the switch W VI a number of times corresponding to the number dialled. In the same manner as that described above, the third train of impulses is transmitted to 25 the rotary magnet D VII.

All the trains of impulses having been stored up, the relay VII is operated; at contact 7' it closes the locking circuit for its winding II, at contact 7 it closes a locking 30 circuit for the relay C, and at contact 7" it prepares a circuit for the relay O. The dialling having been completed, the operator withdraws the plug 1 from the jack W *h* 1, thereby disconnecting the relay U, which 35 switches over its contacts.

When a signalling line becomes free, the relay T falls back and the switches W I and W II move into their normal position. At contact *t* 3 is closed a circuit for energizing 40 the relay G, which at its contact closes the following circuit for the relays O and An 1: battery, back contacts *s* 2 and *u* 2, front contact 7", winding of relay O, front contact *g*, contact O at the third contact set of the switch W I, winding of relay An 1, back contact *t* 1, earth. The relay An 1 at its contact 45 1 *an* 1 closes a locking circuit for itself and for the relay O and in the manner described above it actuates the rotary magnet D I. When the wipers of the switch 50 reach the contacts, to which the leads *a'* and *b'* are connected, the relays T and P are operated in the following route: earth, windings I and II of the relay T, wiper and contact at the second contact set of the switch 55 W I, contact and wiper of the first contact set of the switch W III, back contact *p*, front contact *o* 1, back contact *s* 1, winding of relay P, battery, earth. Relay T and its 60 contact *t* 1 interrupts the circuit of the relays 65 An 1 and O and at contact *t* 3 it interrupts the circuit of relay G. Relay An 1 at its contact 2 *an* *i* disconnects the relay interrupter RU, thereby permanently interrupting the circuit of the relay F and thus also 70 that of the rotary magnet D I. Relay P at its contact *p* closes a locking circuit for itself and at contact *p* 1 it closes a circuit for energizing the impulse relay J 1: battery, back contacts *s* 2, *u* 2, front contacts 75 7" and *p* 1, winding of relay J 1, earth. Relay J 1 at its contact *i* I 1 closes the circuit of the rotary magnet D IV, which moves on its wipers one step and at contact *d* 4 short circuits the relay J 1. The latter 80 therefore falls back and at contact *i* I 1 it opens the circuit of the rotary magnet, which removes the short circuit from the relay J 1. In this manner the relay J 1 and the rotary 85 magnet D IV are alternately energized and deenergized. The rotary magnet moves the switch wipers of the switch W IV step by step. From the second step onwards of the switch W IV the circuit of the relay J 1 extends over: earth, winding of relay J 1, 90 wiper and bank contacts 1-10 of the switch W IV, resistance *W* *i*, battery, earth. The relay J 1 at its contact *i* I 3 closes and opens a circuit for the impulse repeating relay J at the incoming end of the signalling line: 95 earth, back contact *o*, impulse contact *i* I 3, back contact *r* I 1, front contact *p* 2, back contact 2 *an* 2, wiper and bank contact of the switch W III 2, wiper and contact of the switch W I 1, back contact 3 *an* 1, signalling line *a* 1, wiper and contact of the switch W II, winding of relay J, battery, earth. This circuit is kept open when the second wiper of the switch W IV reaches the contact designated by the wiper of the 100 switch W V. Thereupon a circuit for the relay R 1 is prepared, which is closed upon the release of the relay J 1: earth, impulse contact *i* I 2, winding I of the relay R 1, second wiper and contact of the switch W 105 IV, marked contact and wiper of the contact set 1 of the switch W V, battery, earth. Relay R 1 is operated and at contact *r* I 1 it permanently opens the circuit to the impulse repeating relay J. A locking circuit for the second winding of relay R 1 is closed at contact *i* 15, hence the impulse circuit 110 remains open. Only on the switch W IV reaching the eleventh contact does the relay R release its armature, because then the following circuit is closed for the opposing winding III of the relay R 1 I: earth, impulse contact *i* I 2, winding I of relay R 1, wiper and contact 11 of the switch W IV, front contact *r* I, opposing winding III of relay R 1, 115 battery, earth. Contact 11 is a stopping contact. The slow acting relay Q was also energized over the second winding of the relay R 1, and at contact *g* 1 it interrupts 120 the circuit of the impulse relay J 1 over the 125 65 contact *t* 1. Contact *t* 1 interrupts the circuit of the relays 130

eleventh contact. Now when the opposing winding III of relay R 1 is connected up, the relay Q also falls back, and as it is slow to release, the circuit of the relay J 1 remains open for some time. The stopping place is inserted for the purpose of giving time for the switching over of the connecting devices, which at the incoming end of the junction line are positioned by current impulses. After the relay Q has fallen back, the circuit of the impulse relay J 1 is closed again and the second train of impulses is sent to the impulse repeating relay J at the incoming end of the signalling line in the same manner as that described above. Contact 23 likewise forms a stopping place.

The last train of impulses have the same effect on the connecting devices at the incoming end of the signalling line as that described above. After this train has been transmitted, the speaking leads are switched through from the called to the calling subscriber and the conversation can be carried on. At the contact 35 of the switch W IV a circuit is then closed for the first winding of relay S, which is slow to release: earth, impulse contact i 1 2, winding I of relay R, wiper and contact 35 of the switch W IV, winding I of relay S, battery, earth. Relay S at its contact s opens the circuit of the relay C I. Relay C I falls back and its contact c I 4 opens the locking circuit of the second windings of the relays V, VI and VII. At contact c I 3 the following circuit is closed for the relay An 2: earth, back contact u 5, winding of relay An 2, wiper and contact at the third contact set of the switch W III, back contact c I 3, winding I of relay S, battery, earth. Relay An 2 is operated and it connects the relay interrupter RU 1 to the rotary magnet D III. The rotary magnet moves on the wipers of the switch W III until the normal position is reached. The circuit of the relay An 2 is then interrupted and the switch remains standing in its normal position. At contact c I 2 the relay interrupter is connected to the rotary magnet D VII of the switch W VII: earth, relay interrupter RU 1, winding II of the relay S, back contact c I 2, wiper and contact of the switch W VII, 3, winding of the rotary magnet D VII, battery, earth. The rotary magnet D VII is alternately energized and de-energized, and moves on the wipers of the switch W VII until they reach the normal position. Thereupon is opened the circuit of the rotary magnet D VII and of the winding I of the relay VII. The relay VII moves its contact 7 into the normal position and connects the relay interrupter to the rotary magnet D VI, which brings the wipers of the switch W VI into the normal position, wherein the circuit of the rotary magnet D VI and of the relay VI is interrupted.

At contact 6 of the relay VI the relay interrupter RU 1 is now switched over to the rotary magnet D V, which brings the wipers of the switch W V into the normal position. The circuit of the relay S is now interrupted. The above described moving on of the switch W III caused the circuit of the relay T to be interrupted; the relay falls back and at its contact t1 it operates the relay An 1 over: earth, back contact t 1, 75 winding of relay An 1, wiper and contact bank of the third contact set of the switch W I, resistance Wi, battery, earth. The contact of relay An 1 connects the relay interrupter to the relay F, which at its contact 80 f 1 alternately energizes and de-energizes the rotary magnet D I and at contact f 2 alternately energizes and de-energizes the rotary magnet D II. The rotary magnets D I and D II move the wipers of the switches 85 W I and W II as far as the normal position, wherein the circuit of the relay An 1 is interrupted. Now all the devices of the signalling line as well as the storers have returned to the normal position, so that both 90 can be used for another connection. The release of the other junction lines at the end of the conversation takes place in the same manner as that described above.

What is claimed is:

1. In a telephone system, a plurality of outgoing trunks each terminating at the distant end in an automatic switch, a plurality of control lines, means for seizing a trunk, an impulse transmitter, means for connecting the transmitter to an idle control line, an impulse storer, means effective if no control line is available for connecting the impulse transmitter to the impulse storer, means effective if the connection is to the impulse storer for connecting the impulse storer to a control line when one becomes available, means for connecting the distant end of the control line connected with to the switch that terminates the seized trunk, 110 means for operating the switch by digit impulses transmitted over the control line, and means for disconnecting the control line from the switch to render the control line available for further use, without releasing the switch.

2. In a telephone system, a plurality of outgoing trunks each terminating at the distant end in an automatic switch, a plurality of control lines, means for seizing a 120 trunk, an impulse transmitter, means for connecting the transmitter to an idle control line, an impulse storer, means effective if no idle control line is available for connecting the impulse transmitter to the impulse storer, means effective if the connection is to the impulse storer for connecting the impulse storer to an idle control line when one becomes available, means for connecting the distant end of the control line 125

- connected with to the switch that terminates the seized trunk, means for transmitting digit impulses over the control line to operate the switch, means for disconnecting the switch, means for disconnecting the control line from the switch to render the control line available for further use, without releasing the switch, and means for connecting the line to a switch which is operated for releasing the switch.
3. In a telephone system, a plurality of outgoing trunks each terminating at the distant end in an automatic switch, a control line common to said switches for controlling the switches, an impulse transmitter, an impulse storser, means for connecting the transmitter to the control line or to the impulse storser depending upon the busy or idle condition of the control line, and means effective if the connection is to the impulse storser for connecting the impulse storser to the control line when the control line becomes idle.
4. In a telephone system, a plurality of outgoing trunks each terminating at the distant end in an automatic switch, a control line common to said switches for controlling the switches, an impulse transmitter, an impulse storser, means for connecting the transmitter to the control line or to the impulse storser depending upon the busy or idle condition of the control line, means effective if the connection is to the impulse storser for connecting the impulse storser to the control line when the control line becomes idle, and means for preventing the impulse storser from being connected to the control line, until a certain number of digits have been stored.
5. In automatic telephone system, a plurality of outgoing trunks each terminating at the distant end in an automatic switch, a control line common to said switches for controlling said switches, an impulse transmitter, an impulse storser, means responsive to the seizure of a trunk for connecting the transmitter to the control line or to the storser depending upon the busy or idle condition of the control line, means effective if the connection is to the storser for connecting the storser to the control line when the control line becomes idle, means for connecting the control line to the automatic switch terminating the seized trunk, and means for transmitting digit impulses over the control line from the transmitter or from the storser depending upon which is connected to the control line, for operating the switch terminating the seized trunk.
6. In a telephone system, a plurality of outgoing trunks each terminating at the distant end in an automatic switch, a control line common to said switches for controlling said switches, an impulse transmitter, an impulse storser, means responsive to the seizure of a trunk for connecting the transmitter to the control line or to the storser depending upon the busy or idle condition of the control line, means effective if the connection is to the storser for connecting the storser to the control line when the control line becomes idle, means for connecting the control line to the automatic switch terminating the seized trunk, and means for disconnecting the control line from the automatic switch without releasing the switch, and means for connecting the line to a switch which is operated for releasing the switch.
8. In a telephone system, a plurality of trunks each terminating in an automatic switch at the distant end, a control line common to said switches, an impulse transmitter associated with one of the trunks, means for connecting the impulse transmitter to the control line, an impulse storser, means for connecting the impulse storser to the impulse transmitter when the control line is busy, means effective when the control line becomes idle for connecting the storser to the control line, and means for operating the automatic switch that terminates the trunk with which the impulse transmitter was associated, by digit impulses transmitted over the control line.
9. In a telephone system wherein a common control line is automatically connected to a digit impulse transmitter, and upon the termination of the transmission of the digit impulses is released, the combination of an impulse storser, means effective if the control line is busy when the impulse transmitter is taken into use for preventing the control line from being connected to the transmitter, and for connecting instead the impulse

storer, means effective when the line becomes free for connecting the impulse storer to the line, and means effective when the impulses stored have been transmitted for releasing 5 the connection.

10. In a telephone system, a switch which is operated by digit impulses and over which talking connections are established, an impulse transmitter, an impulse storer, means for setting up an impulsing circuit from the transmitter to the switch or to the impulse storer depending upon the existence of predetermined conditions, and means effective if the connection is to the impulse

15 storer for establishing an impulsing circuit from the storer to the switch for operating said switch upon the occurrence of predetermined conditions.

11. In a telephone system, a switch which 20 is operated by digit impulses and over which talking connections are established, an impulse transmitter, an impulse storer, means for setting up an impulsing circuit from the transmitter to the switch or to the impulse storer depending upon the existence of predetermined conditions, means effective if the connection is to the impulse storer for establishing an impulsing circuit from the storer to the switch for operating said switch upon 25 the occurrence of predetermined conditions, and means for preventing the establishment of the last named connection until a certain number of digits have been stored

12. In a telephone system, an impulse 30 transmitter, a control line, an impulse storer, means for connecting the transmitter to the control line or to the storer depending upon predetermined conditions and means for indicating to a party at the transmitter the establishment of a connection regardless of 35 those conditions.

13. In a telephone system, an impulse transmitter, a control line, an impulse storer, means for connecting the transmitter to the

line if the line is idle and to the impulse 45 storer if the line is busy.

14. In a telephone system, an impulse transmitter, a control line, an impulse storer, means for connecting the transmitter to the line if the line is idle and to the impulse 50 storer if the line is busy to a party at the transmitter, and means for indicating alike to a party at the transmitter the establishment of either of the two connections.

15. In a telephone system, a plurality of 55 trunks each terminating in a separate automatic switch, a control line common to said trunks, means effective when one of said trunks is taken into use for temporarily rendering said control line individual to the 60 trunk in use, an impulse transmitter, an impulse storer, and means including said transmitter or said storer for transmitting impulses over said control line to operate the switch associated with the trunk in use dependent upon whether said transmitter or 65 said storer is connected with said control line.

16. In a telephone system wherein a plurality of trunks terminate in automatic 70 switches arranged to be controlled by impulses transmitted by an impulse transmitter and by impulses transmitted by a combined impulse storer and sender over a control line common to said trunks, means effective 75 when a trunk is taken into use for connecting the control line with the trunk and transmitter in case the control line is idle, means effective in case the control line is busy for connecting the transmitter with 80 the combined storer and sender to temporarily store the impulses transmitted by the said transmitter, and means for connecting the combined storer and sender with the control line when the control line becomes idle. 85

In witness whereof, I hereunto subscribe my name this 30th day of May, A. D. 1927.

MAX LANGER.
